LUMINAIRE LENS

Kurt Franck and Vearl S. Wince, Newark, Ohio, assignors to Holophane Company, Inc., New York, N.Y., a corporation of New York

Filed Mar. 6, 1959, Ser. No. 54,881

Term of patent 14 years

(Cl. D48—16)

Fig. 1 is a perspective view of a luminaire lens embodying our new design;

Fig. 2 is a side view of one half-section of the lens;

Fig. 3 is an end view of the lens;

Fig. 4 is an elevation thereof as seen from the right of Fig. 3;

Figs. 5 to 9 are enlarged views of the portions of the lens shown in rectangles 5 to 9 of Fig. 1;

Fig. 10 is a sectional view taken along the line 10-10 of Fig. 5; and

Fig. 11 is a sectional view taken along the line 11-11 of Fig. 7.

We claim:

The ornamental design for a luminaire lens, as shown.
